UNITED STATES PATENT OFFICE.

THOMAS G. CLIFFORD, OF HOBOKEN, NEW JERSEY, ASSIGNOR OF ONE-
THIRD TO GARRETT F. ROSE, OF NEW YORK, N. Y., AND ONE-THIRD
TO WILLIAM CRANSTOUN, OF SUMMIT, NEW JERSEY.

NON-REFILLABLE BOTTLE.

No. 803,992.

Specification of Letters Patent.

Patented Nov. 7, 1905.

Application filed February 10, 1905. Serial No. 245,003.

To all whom it may concern:

Be it known that I, THOMAS G. CLIFFORD, a citizen of the United States, residing at Hoboken, in the county of Hudson and State of New Jersey, have invented a new and useful Improvement in Non-Refillable Bottles; and I do hereby declare the following, when taken in connection with the accompanying drawings and the figures of reference marked thereon, to be a full, clear, and exact description of the same, and which said drawings constitute part of this specification, and represent, in—

Figure 1, a vertical central section of the upper part of a bottle, showing my improved non-refilling device therein; Fig. 2, a side view of the non-refilling device detached; Fig. 3, a similar view turned one-quarter around; Fig. 4, a side view, partially in section, of a modified form of my improved non-refilling device.

This invention relates to an improvement in non-refillable bottles, and particularly to that class in which a cage or trap is arranged within the neck of the bottle, so that while the contents of the bottle may be readily removed it is impossible to refill it, the object of the invention being a simple arrangement of parts whereby these results are accomplished; and the invention consists in the construction as hereinafter described, and particularly recited in the claims.

In carrying out my invention I form a bottle 2 of any desired shape, having a substantially straight neck 3, with an internal annular rib or shoulder 4 within the lower end of the neck, this rib being formed during the manufacture of the bottle. Within the neck is a cage consisting of a shell 5, corresponding substantially in diameter to the internal diameter of the neck of the bottle, and an upwardly-extending stem 6. This stem being hollow opens into the shell 5, is closed at its upper end, and is provided with numerous perforations 7 in its sides. Within the shell is a lug 8, to which a valve 9 is pivoted, this valve being flat and bearing at one side against the under side of the lug and at the opposite side resting upon the lower edge of the shell, which at one side is cut away, giving access to the interior of the shell. At the lower end of the outside of the shell is an opening 10

to receive one end of a wire hook 11, which is of substantial S-shape, the lower end of the hook being adapted to engage with the rib 4. The shell is secured in the neck of the bottle by a film 12, of glass, cement, or other suitable material, and this cement in itself may be sufficient to hold the shell in the neck; but I generally prefer to also employ the wire hook. Instead of forming the stem 6 cylindrical it may be conical, as shown in Fig. 4, and instead of forming the lug 8 integral with the shell 5 it may be formed independently thereof and secured thereto by cement or otherwise, as also shown in Fig. 4.

It will be understood that the device is arranged so far below the upper end of the neck of the bottle that the usual stopper of cork or other material may be placed in the mouth of the bottle, so as to securely close the same. When the bottle is tilted, the valve 9 will turn, allowing the contents of the bottle to pass into the shell 5, from thence into the stem 6, and escape through the opening 7, thus giving a free discharge for the contents of the bottle. Should, however, an attempt be made to refill the bottle, the passage of liquid into the neck of the bottle will securely close the trap 9, and thus prevent the entrance into the body of the bottle. The openings in the stem are so arranged and so distant from the valve that it is impossible to insert any instruments through the openings, so as to manipulate the valve and hold it open. 85

Having fully described my invention, what I claim as new, and desire to secure by Letters Patent, is—

1. A non-refillable bottle comprising a body and a neck, a shell open at the bottom located in said neck and attached thereto, a hollow stem arising from said shell-opening at the bottom into said shell and closed at its upper end, said stem formed with openings in its sides, and a valve secured at the lower end of said shell to close the opening in the bottom thereof, substantially as described. 90

2. A non-refillable bottle comprising a body and a neck, a shell rigidly secured in said neck and formed with an opening at the bottom, a hollow stem above said shell with which it is connected at its lower end, said stem closed at its upper end and formed with perforations in its sides, a lug in said shell, and a valve 100

connected with the under face of said lug and adapted to close the opening in the bottom of the shell, substantially as described.

3. A non-refillable bottle comprising a body 5 and a neck, said neck formed with an internal rib, a shell open at the bottom and secured in said neck above said rib, a stem above said shell and opening thereinto, said stem closed at its upper end and formed with openings in 10 its sides, a valve in said shell adapted to close the opening in the bottom thereof, and a wire

hook engaging with the lower end of the said shell and with said rib, substantially as described.

In testimony whereof I have signed this 15 specification in the presence of two subscribing witnesses.

THOMAS G. CLIFFORD.
